UNITED STATES PATENT OFFICE

GEORGE W. BAUGHMAN, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY TRAFFIC CONTROLLING APPARATUS

Application filed June 18, 1930. Serial No. 461,967.

My invention relates to railway traffic controlling apparatus, and particularly to automatic train control systems of the code type.

One feature of my invention is the provision in systems of this type, of novel and improved trackway means for insuring the pick-up of a track relay on coded current after the removal of a shunt across the track rails.

10 I will describe one form of apparatus embodying my invention, and will then point out the novel features thereof in claims.

The accompanying drawing is a diagrammatic view showing one form of trackway apparatus embodying my invention.

Referring to the drawing, the reference characters 1 and 1^a designate the track rails of a railway track along which traffic normally moves in the direction indicated by the arrow. These rails are divided by insulated joints 2 to form a series of track sections, of which only one complete section A—B is shown in the drawing.

Located at the entrance end of the section 25 A—B is a source of alternating track circuit current, and this source, as here shown, is a transformer E, the secondary 16 of which is connected across the track rails through a current-limiting impedance 17, and the primary 20 15 of which transformer is constantly connected with terminals X and Y of a source of alternating current. Located at the exit end of the section A—B is a track relay R comprising two windings 3 and 4 and a rotor 25 member 5 which operates two contacts 6 and 7. Relay winding 3 is constantly connected across the track rails through the secondary 9 of a train-controlling transformer T. The primary 8 of the transformer T and the sec- 40 ond winding 4 of the track relay R are connected in series across the terminals X and Y of the same source of current as that which supplies the track transformer E.

When the track relay R is energized, so that 45 the front points of its contacts 6 and 7 are closed, the junction point 18 of the transformer primary 8 and the track relay winding 4 is connected through the front point of contact 6 with terminal X of the source of current, so that transformer primary 8 is then

placed on short circuit, with the result that said primary is deenergized. Current is then supplied to relay winding 4, with the result that this winding is energized.

The reference character C designates a 55 coding device comprising an electric motor 10, a cam 11 driven by motor 10, and a follower 12 cooperating with the cam 11 and operating a contact 13. When relay R is energized, the coding device is deenergized, 60 so that it is at rest. When relay R becomes deenergized, however, so that the back point of contact 6 closes, motor 10 is connected with the terminals X and Y of the source of alternating current so that this motor is then 65 energized to operate the cam 11 and so to oscillate the contact 13. The supply of train governing current to the rails of section A—B is controlled in part by the contact 13 of the coding device C, and in part by a contact 14 70 of a relay D which is governed by traffic conditions in advance of section A—B.

As shown in the drawing, section A—B is unoccupied so that relay R is energized, with the result that coding device C is at rest and the train control transformer T is deenergized. If now a train moving in the direction indicated by the arrow enters section 75 A—B, it will shunt the track circuit current from track relay winding 3, with the result that this relay will become deenergized. When the back point of contact 6 closes, coding device C will be set into operation to cause contact 13 to oscillate. Assuming that relay D is energized, as shown in the drawing, 80 then when contact 13—13^a is closed, the junction point 18 will be connected with terminal Y of the source of current through the front point of contact 14 of relay D, contact 13—13^a of the coding device C, and the back point 85 of contact 7 of relay R. At this time the primary 8 of transformer T will be connected with terminals X and Y of the source of current, whereas both terminals of track relay winding 4 will be connected with terminal Y of the source of current so that this winding will be placed on short circuit.

When contact 13—13^b closes, however, the junction point 18 will be connected with terminal X of the source of current so that 90 95 100

transformer primary 8 will be placed on short circuit and relay winding 4 will be supplied with current. In other words, the windings 8 and 4 will be alternately energized, so that alternating current will be periodically supplied to the rails of section A—B for the control of the train-carried apparatus. When the front end of the train leaves section A—B, it will open relay D, and when the rear end of the train leaves this section, point 18 will be connected with terminal X through the back point of contact 14 of relay D. Relay R will then become energized because of the continuous supply of alternating current to its winding 4, whereupon the apparatus will be restored to its normal condition.

When a shunt is removed from the rails of section A—B while relay D is energized, it becomes necessary for relay R to pick up on the coded current. Heretofore when a code system of train control has been applied to a reversed track circuit, the circuits for relay winding 4 and primary winding 8 have been separate and independent, and in such cases it has been found necessary to apply more than normal energy to the track relay in order to cause the relay to become energized during the "off" period of the code, this being due to a strong kick in the reverse direction received by the relay during the "on" period of the code. With apparatus embodying my invention this kick is very materially reduced, and I have found that relay R will become effectively energized without delay by the coded current immediately after a shunt across the rails has been removed.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a section of railway track, a source of alternating track circuit current connected across the rails at one end of said section, a track relay having two windings one of which is connected across the rails at the other end of said section, a train control transformer the secondary of which is interposed between the said one winding of said relay and one of the track rails, a circuit extending from the first terminal of a source of alternating current through the primary of said transformer and the second winding of said relay to the second terminal of said source, means operating when said track relay is closed to connect the junction of said primary and said second relay winding with the first terminal of said source whereby the primary is then on short circuit, and means oper-

ating when said track relay is open to alternately connect said junction with the two terminals of said source whereby the primary and the second relay winding are alternately energized and each is on short circuit while the other is energized. 70

2. In combination, a section of railway track, a source of alternating track circuit current connected across the rails at one end of said section, a track relay having two windings, one of which is connected across the rails at the other end of said section, a train control transformer the secondary of which is interposed between one of the track rails and said one relay winding, a circuit including the primary of said transformer and the second relay winding connected in series across a source of alternating current, means operating when said relay is closed to place said primary on short circuit, and means operating when said relay is open to alternately place said primary and said second relay winding on short circuit. 75 80 85

3. In combination, a section of railway track, a source of alternating track circuit current connected across the rails at one end of said section, a track relay having two windings one of which is connected across the rails at the other end of said section, a train control transformer the secondary of which is interposed between one of the track rails and said one relay winding, a circuit including the primary of said transformer and the second relay winding connected in series across a source of alternating current, means operating when said relay is closed to place said primary on short circuit, a coding device comprising a motor and a contact periodically operated thereby, means for energizing said coding device when said track relay is open, and means including said contact and operating when said relay is open to alternately place said primary and said second relay winding on short circuit. 90 95 100 105

In testimony whereof I affix my signature. 110
GEORGE W. BAUGHMAN.
